UNITED STATES PATENT OFFICE.

CLEMMA R. RANEY, OF CHICAGO, ILLINOIS, ASSIGNOR TO INTERNATIONAL HARVESTER COMPANY OF NEW JERSEY, A CORPORATION OF NEW JERSEY.

BINDER-LOCKING MECHANISM.

1,242,240.

Specification of Letters Patent.

Patented Oct. 9, 1917.

Application filed May 13, 1914, Serial No. 838,244. Renewed March 28, 1917. Serial No. 158,114.

To all whom it may concern:

Be it known that I, CLEMMA R. RANEY, a citizen of the United States, residing at Chicago, in the county of Cook and State of Illinois, have invented certain new and useful Improvements in Binder-Locking Mechanism, of which the following is a full, clear, and exact specification.

My invention relates to binder locking mechanism especially adapted to use in connection with grain or other shocking machines.

In the use of a binder in connection with a shocker, it has heretofore been proposed to provide mechanism for locking the sheaf discharging mechanism of the binder after the sheaf has been bound and prior to the completion of the sheaf discharging operation, until the sheaf delivery member of the shocker is in position to receive that sheaf, the said mechanism comprising a supplemental clutch controlling member and operative connections therefor whereby that member is thrown into engagement with the rotating element of the binder clutch alternately with the ordinary clutch controlling member and at a time intermediate the ends of the normal cycle of operation of the clutch, the movement of the sheaf discharge arms being thereby interrupted after a fractional part of the normal movement of the same until the sheaf delivery member of the shocker has returned to its sheaf receiving position and actuated certain tripping mechanism operatively connected to the supplemental clutch controlling member to disengage the latter from the clutch, whereupon the discharge arms complete their discharging movement and deliver the sheaf to the sheaf delivery member then in position to receive it.

My invention has for its object to provide improved connections for such a mechanism whereby the parts are allowed greater resiliency and flexibility in operation and are at the same time rendered capable of adjustment and more certain in their operation, so that all tendency for the same to catch or to operate out of their desired sequence is effectually prevented.

I attain these objects by providing im-

proved connections directly connected between the supplemental clutch controlling member and a positively driven part of the binder mechanism whereby the movement of this clutch controlling member is controlled and the above mentioned ends are obtained, all as hereinafter more fully set forth.

In accordance with the requirements of the patent statutes, I shall hereinafter set forth a specific description of one embodiment of my invention in order that the same may be fully and clearly disclosed, using this embodiment as an illustration of the principle of the invention and not limiting the invention to the form described.

In the accompanying drawings—

Figure 1 is a front elevation of a binder equipped with my improvement;

Fig. 2 is a side elevation of a portion of the mechanism shown in Fig. 1, the view being taken from the delivery side of the binder deck.

The binder and shocker mechanisms shown are of standard construction and *per se* form no part of my present invention. As illustrated, the binder includes a machine frame 1 having a binder deck 2, a binder supporting frame 3 and a binder frame 4. Carried by this frame, above the supporting frame 3 and adjacent the deck 2, is the usual sheaf forming and binding mechanism of the binder comprising the packers 5 carried on the packer shaft 6, a needle 7 carried on the needle shaft 8, the compressor trip 9 carried on the compressor shaft 10, the link connections 11 between the needle and the usual cam wheel 12, and the resilient link connections 13—14 between the clutch controlling member 15 and this cam wheel. Further, as in the usual construction, to cooperate with the binding mechanism mentioned a suitable knotter is also provided including a knotter shaft 17 operatively connected to the cam wheel 12, and a breast plate 18, as well as sheaf discharging mechanism including discharge arms 19 carried on the knotter shaft 17.

In this binder mechanism the clutch controlling member 15 is splined to the compressor shaft 10 and engageable with the

rotating finger 20 of the binder clutch 16, as in the usual construction, being thrown out of engagement with this clutch finger by the depression of the compressor trip 9 so as 5 to enable the clutch finger 20 to rotate through three complete revolutions during the operation of the binding and discharging mechanism. Also coöperating with this mechanism is a binder locking mechanism 10 of the Raney, Benjamin and Livesay type, which includes a supplemental clutch controlling member 21 operatively connected to the mechanism above mentioned, and through supplemental link mechanism 22 connected 15 to a trip 23 carried on a supplemental support 24 protruding from beneath the binder deck 2; which trip is adapted to be actuated by the sheaf delivery member 25 of a shocker at intervals, the sheaf delivery member being 20 operatively connected through mechanism (not shown) to swing back and forth in a substantially upright plane while discharging sheaves to the shock receptacle (not shown) when a sheaf discharged by the 25 sheaf discharging arms 19 actuates any suitable controlling member, such as the member 26 projecting upward on the stubbleward side of the sheaf delivery member and pivotally mounted at 27 on the support 24.

30 In the binder lock construction acknowledged above, a pin is provided on the stubbleward end of the clutch controlling member 15, which pin acts to raise the clutch controlling member 21 as the former member is moved into clutch engaging position. In my improvement, in lieu of this pin connection, I provide improved lifting means and an improved resilient connection of the parts of the mechanism. In the embodiment 35 of that improvement illustrated herein I show a supplemental upstanding link 28 having its upper end pivotally connected at 29 to the pivot of the link 14 on the cam engaging link 13 and extending downwardly 40 alongside the link 14 in front of the supplemental clutch controlling member 21, the link 28 being slightly bowed intermediate its ends, as shown in Fig. 2, in order to enable it to clear the supplemental clutch controlling member 21. Carried upon the lower end of this link 28 is a supplemental U-shaped member 30 having eyes 31 on its ends through which the link 28 is passed. Through this U-shaped member and between 45 the same and the link 28, the clutch controlling member 21 extends, as shown in Fig. 2. A coiled spring 32 is also preferably provided on the lower end of the link 28, which spring engages the lower eye of the member 30 and is adjustable in its contact therewith through a tension adjusting connection 33.

50 In the operation of my improved construction it is, of course, to be understood that the binder and binder locking mecha-

nism of the shocker operate in substantially the same manner that they do in the construction acknowledged above, the clutch controlling member 15 being raised out of engagement with the clutch finger 20 when 55 the compressor trip 9 is depressed and the clutch controlling member 21 being thrown into engagement with the clutch finger after the latter has completed substantially two-thirds of its normal rotation; *i. e.*, when the 60 sheaf discharging arms 19 occupy the lower dotted line position shown, the parts remaining in that position until the sheaf delivery member 25 returns to its lower dotted line position when, through the trip 23 and 65 the link connections 22, the supplemental clutch controlling member 21 is thrown out of engagement with the clutch finger 20 in such a manner as to enable the sheaf discharge arms 19 to complete their normal 70 cycle of operation and move to the upper dotted line position shown in discharging a sheaf upon the sheaf delivery member 25.

In the course of this operation it is to be noted, however, that as the link 13 is raised in returning the compressor trip 9 to its normal or up position to compress the bundle during the tying of the knot and to be acted upon by the grain of the next sheaf, and also to return the clutch controlling 75 member 15 to clutch engaging position, the link 28 is raised and, through the provision of the member 30, an upward pull is exerted on the supplemental clutch controlling member 21, which acts to raise this member, but 80 at the same time allows a certain amount of yielding movement, greatly adding to the flexibility of the parts and effectually preventing any breakage or derangement of the same should a clutch controlling member 85 stick at any point in its operation. It is further to be noted that through the adjustment of the spring 32 the clutch controlling member 21 may always be timed accurately with respect to the other coöperating 90 parts of the mechanism and to the clutch finger 20, the spring, when adjusted as desired, tending to maintain the members 12 and 21 operating in the desired sequence, while through the provision of the member 95 30, certainty of movement of member 21 is insured and a connection is provided which is sure in its operation and the parts of which are not liable to loss, derangement or wear in service. These and other advantages of my improved construction will be 100 clearly apparent to those skilled in the art.

Having now described one embodiment of my invention with a reiteration of my intent that the form described is to be considered as shown only for purposes of illustration, I will now proceed to claim my invention.

1. In combination, sheaf forming and binding mechanism, a binder clutch, a clutch

65 130

controlling member, operative connections between the same and a movable part of said sheaf forming and binding mechanism, a supplemental clutch controlling member, and 5 supplemental means directly connecting the same to said movable part.

2. In combination, sheaf forming and binding mechanism, a binder clutch, a clutch controlling member, operative connections 10 between the same and a positively driven part of said sheaf forming and binding mechanism, a supplemental clutch controlling member, and supplemental adjustable means directly connecting the same to said 15 positively driven part.

3. In combination, sheaf forming and binding mechanism, a binder clutch, a clutch controlling member, operative connections 20 between the same and a positively driven part of said sheaf forming and binding mechanism, a supplemental clutch controlling member, a link directly connected to said positively driven part, and a resilient connection between said link and said supplemental clutch controlling member.

4. In combination, sheaf forming and binding mechanism, a binder clutch, a clutch controlling member operatively connected to said sheaf forming and binding mechanism, a supplemental clutch controlling member, means for throwing said clutch controlling members alternately into engagement with said clutch, and yielding operative connections between said supplemental clutch controlling member and an intermittently movable part of said sheaf forming and binding mechanism.

5. In combination, sheaf forming and binding mechanism, a binder clutch, a clutch 40 controlling member operatively connected to said sheaf forming and binding mechanism, a supplemental clutch controlling member, means for throwing said clutch controlling members alternately into engagement with said clutch, and resilient operative connections between said supplemental clutch controlling member and an intermittently movable part of said sheaf forming and binding mechanism.

50 6. In combination, sheaf forming and binding mechanism, a binder clutch, a clutch controlling member operatively connected to said sheaf forming and binding mechanism, a supplemental clutch controlling 55 member, means for throwing said clutch controlling members alternately into engagement with said clutch, and a link operatively connected to said supplemental clutch controlling member and an intermittently movable part of said sheaf forming and binding mechanism.

7. In combination, sheaf forming and binding mechanism, a binder clutch, a clutch controlling member operatively connected 60 to said sheaf forming and binding mechanism.

65 to said sheaf forming and binding mecha-

nism, a supplemental clutch controlling member, means for throwing said clutch controlling members alternately into engagement with said clutch, a link operatively connected to an intermittently movable part of said sheaf forming and binding mechanism, and a resilient connection intermediate said link and said supplemental clutch controlling member.

8. In combination, binding mechanism including a clutch, a clutch controlling member, a compressor trip, a cam wheel, operative connections between said cam wheel and said compressor trip, a supplemental clutch member, means for throwing said clutch members alternately into engagement with said clutch, and resilient connections for said supplemental clutch member operatively connected to the operative connections for said compressor trip.

9. In combination, binding mechanism including a clutch, a clutch controlling member, a compressor trip, a cam wheel, operative connections between said cam wheel and said compressor trip, a supplemental clutch member, means for throwing said clutch members alternately into engagement with said clutch, and a link carried on the operative connections between said compressor trip and said cam wheel resiliently connected to said supplemental clutch controlling member.

10. In combination, binding mechanism including a clutch, a clutch controlling member, a compressor trip, a cam wheel, operative connections between said cam wheel and said compressor trip, a supplemental clutch member, means for throwing said clutch members alternately into engagement with said clutch, a link carried on said operative connections between said compressor trip and said cam wheel, and a U-shaped member carried on said link engageable with said supplemental clutch controlling member.

11. In combination, sheaf forming and binding mechanism, a binder clutch, a clutch controlling member operatively connected to said sheaf forming and binding mechanism, a supplemental clutch controlling member, means for throwing said clutch controlling members alternately into engagement with said clutch, a link operatively connected to an intermittent movable part of said sheaf forming and binding mechanism, and a resilient mounted connecting member connecting said link and said supplemental clutch controlling member and slidably mounted on said link.

12. In combination, sheaf forming and binding mechanism, a binder clutch, a clutch controlling member operatively connected to said sheaf forming and binding mechanism, a supplemental clutch controlling member, means for throwing said clutch

controlling members alternately into engagement with said clutch, means for connecting said supplemental clutch controlling member with said clutch alternately with respect to member to an intermittently moving part, said first mentioned clutch controlling member of said sheaf forming and binding mechanism, and an adjustable connection between said last mentioned means and said clutch controlling member.

13. In combination, a frame, a binder cam wheel, a member pivoted on said frame engageable with the cam on said wheel, a binder clutch, a clutch controlling member pivoted on said frame, a connection between said clutch controlling member and said cam engaging member, a supplemental clutch controlling member pivoted on said frame, mechanism for throwing said supplemental clutch controlling member into engagement with said clutch alternately with respect to said first mentioned clutch controlling member.

14. In combination, a frame, a binder cam wheel, a member pivoted on said frame engageable with the cam on said wheel, a binder clutch, a clutch controlling member pivoted on said frame, a resilient connection between said clutch controlling member and said cam engaging member, a supplemental clutch controlling member pivoted on said frame, mechanism for throwing said supplemental clutch controlling member into engagement with said clutch alternately with respect to said first mentioned clutch controlling member, and a supplemental yieldable connection between said supplemental clutch controlling member and said cam engaging member.

15. In combination, a frame, a binder cam wheel, a member pivoted on said frame engageable with the cam on said wheel, a binder clutch, a clutch controlling member pivoted on said frame, a resilient connection between said clutch controlling member and said cam engaging member, a supplemental clutch controlling member pivoted on said frame, mechanism for throwing said supplemental clutch controlling member into engagement with said clutch alternately with respect to said first mentioned clutch controlling member, and a supplemental yieldable connection between said supplemental clutch controlling member and said cam engaging member.

16. In combination, a frame, a binder cam wheel, a member pivoted on said frame engageable with the cam on said wheel, a binder clutch, a clutch controlling member pivoted on said frame, a connection between said clutch controlling member and said cam engaging member, a supplemental clutch controlling member pivoted on said frame, mechanism for throwing said supplemental clutch controlling member into engagement with said clutch alternately with respect to said first mentioned clutch controlling member, and a supplemental link operatively connected at one end to said cam engaging member.

17. In combination, a frame, a binder cam wheel, a member pivoted on said frame engageable with the cam on said wheel, a binder clutch, a clutch controlling member pivoted on said frame, a connection between said clutch controlling member and said cam engaging member, a supplemental clutch controlling member pivoted on said frame, mechanism for throwing said supplemental clutch controlling member into engagement with said clutch alternately with respect to said first mentioned clutch controlling member, and a supplemental link operatively connected at one end to said cam engaging member.

18. In combination, a frame, a binder cam wheel thereon, a member pivoted on said frame engageable with said cam wheel, a binder clutch on said frame, a clutch controlling member, a connection between said clutch controlling member and said cam engaging member, a supplemental clutch controlling member carried on said frame, and a supplemental

19. In combination, a frame, a binder cam wheel, a member pivoted on said frame engageable with the cam on said wheel, a binder clutch, a clutch controlling member operatively connected to said sheaf forming and binding mechanism, a supplemental clutch controlling member, means for throwing said clutch controlling members alternately into engagement with said clutch, a link operatively connected at its upper end to an intermittently movable part of said sheaf forming and binding mechanism, a U-shaped member slidable on said link extending around said supplemental clutch controlling member, and a coiled spring carried on the lower member.

20. In combination, binding mechanism including a clutch, a clutch controlling member, a compressor trip, a cam wheel, operative connections between said cam wheel and said compressor trip, a supplemental

clutch member, means for throwing said clutch members alternately into engagement with said clutch, a link movable with the operative connections between said compressor trip and said cam wheel, a U-shaped member carried on said link engageable with said supplemental clutch controlling member, and a spring carried on said link nor-

mally positioning said U-shaped member thereon. 10

In testimony whereof I affix my signature, in the presence of two witnesses.
